UNITED STATES PATENT OFFICE.

HERMAN L. KUTTER, OF HAMILTON, OHIO.

BEARING.

Application filed December 26, 1923. Serial No. 682,685.

This invention relates to improved type of bearing, and more particularly to a type of bearing for use in connection with paper-making machinery.

5 One of the principal objects of the invention is to provide a bearing, such as may be used for supporting the table rolls and the like of a paper-making machine, which is simple in construction, easy of 10 manufacture, long lived, and readily maintained in operating condition.

Another object of the invention is to provide a bearing for the table rolls, or the like, of a paper-making machine, which is 15 so constructed that easy mounting of the rolls and ready adjustment of the bearings and rolls may be secured, and that rotation of any one roll will cause positive driving of the remaining rolls.

20 Other objects and advantages of the invention will be apparent from the description thereof set out below, when taken in connection with the accompanying drawing.

In the drawing, in which like characters 25 of reference designate like parts throughout the several views thereof,

Fig. 1 is a vertical sectional view through a form of bearing for the table rolls of a paper-making machine constructed in accordance with this invention, the section being substantially along the line 1—1 of 30 Fig. 3;

Fig. 2 is a vertical sectional view along the line 2—2 of Fig. 1, looking in the direction of the arrows; and

Fig. 3 is a vertical sectional view along the line 3—3 of Fig. 1, looking in the direction of the arrows.

As showing a preferred embodiment the 40 invention is illustrated and described herein as embodied in a bearing for supporting the table rolls which are generally used in paper-making machinery, particularly in the shaking or forming section of a Fourdrinier type of machine. It is to be understood, however, that the invention is not limited in its application to the precise embodiment shown.

As is well known, in a Fourdrinier type 50 machine the stock is flowed onto an endless forming wire, which travels at the desired rate of speed over a series of rolls which are rotatably mounted upon, what for convenience is called herein, the "forming section" of the machine. These table rolls should rotate freely at all times, for they

are driven solely by the frictional drag of the forming wire as it passes over them. If any roll should stick the drag on the wire would be increased which is objectionable, and furthermore the wire as it passes over the surface of this roll would tend to wear a flat place on it. Table rolls are generally provided with a supporting shaft or journal at each end, each journal being 60 adapted for positioning within a yoke shaped bearing carried by the side rail of the forming section. Each forming section will have some thirty or forty of these rolls and a like number of bearings on each 65 side and each bearing must ordinarily be lubricated separately. It is very easy, therefore, to fail of keeping all of the bearings lubricated and excessive wear is consequently quite general with respect to some 70 of the bearings, and as soon as such wear occurs the corresponding table roll drops down out of contact with the forming wire so that it is no longer driven. The wire is therefore unsupported as it should be and 75 defects in the paper may result. These table rolls are often twenty feet or more in length. In practice the forming wire wears out rather quickly and must be replaced every few weeks. With the ordinary type 80 of machine all of the table rolls are removed when the forming wire is replaced. And it is not very easy, even for skilled workmen, in attempting to remove and replace these 85 table rolls quickly, to replace them without jamming some of the rolls because of failure to properly enter the journal into the yoke bearing. Furthermore with this general type of construction described it is very difficult to keep the parts in alignment, 90 especially in a shaking type of Fourdrinier, because of the shaking to which the parts are subjected. It is also extremely difficult to keep water out of the bearing, and this 95 causes trouble.

The type of bearing which is shown herein is adapted to obviate all of the difficulties present in bearings used heretofore, whether of the yoke type, or any other type; for all bearings heretofore used have been subject 100 to certain objectionable defects.

As shown in the drawing this bearing comprises a split housing having a lower body portion 10 and an upper cover portion 11 these two portions being held 110 together when in operative position by means of suitable bolts 12. This housing

is supported from the side, shaking, rail 13 by means of brackets 14, one of which is positioned at each end of the housing, each of these brackets being suspended from the 5 downwardly projecting flange of the suspension plate 16, by means of a bolt 17, the plate 16 being in turn held to the side rail by means of the bolt 18. By means of this construction the housing may be adjusted 10 to any desired positioning for the plate 16 may be turned about the bolt 18 and the bracket 14 may be swung about the bolt 17 and both the plate and the bracket may be locked in any desired positioning by suitable 15 tightening of the bolts 17 and 18. Extending through the lower end of each bracket is an adjusting screw 20 each of which contacts with, and supports one end of, the housing, suitable up and down movement of either or both ends of the housing 20 thus being provided for to give further adjustability. Lock nuts 21 for holding the supporting screws 20 in adjusted position are also provided.

25 Preferably suitable dowel pins 22 and 23 are provided for locking each bracket and its associated supporting plate in definite adjusted position, after the housing and the bearings therein have been properly adjusted. After the housing and bearings are once suitably adjusted this adjustment need not be varied over long periods of time; for the table rolls may be removed and replaced as often as desired over long periods 30 of operation without substantially varying their adjustment relative to each other and with respect to the path of travel of the forming wire.

As shown the housing is constructed to receive, in bearing relation, three table rolls; but within certain practical limits any desired number of table rolls may be supported by one housing. The number of table rolls supported by a given housing is dependent 40 upon the diameter of the rolls, and is also limited by certain practical factors such as the limitations in physical strength of the materials used. And so for purposes of disclosure the housing is shown as supporting only three table rolls.

50 Mounted within the body portion 10 of the housing are a number of rollers bearings, there being one more roller bearing than there are table rolls to be supported and the bearings being so positioned that each table roll is supported by two adjacent bearings. Regardless of how many rolls are supported by a given housing there will be one more bearing than there are table rolls. 55 The several bearings shown are of the roller type but of course ball bearings or other suitable type of bearings may be used. Each bearing consists of an inner-race 30 which is in the form of a bolt, extending through 60 each side wall of the lower portion of the

housing. This bolt is provided at one end with a head 31, and at its other end with a threaded extension 32, upon which is positioned a suitable nut 33. By proper manipulation of the nuts 33 the bolts 30 may be entirely removed, or properly tightened in position. Surrounding the inner-race in suitable spaced relation therewith is an outer-race or bearing sleeve 35. Positioned between the inner and the outer race are rollers 36, which are held in position by means of suitable retaining rings 37. Any suitable type of roller may be used, other than that shown in the drawing, but the type of roller shown has been found to function very satisfactorily. The bearing sleeve 35 not only constitutes the outer-race and retaining ring for the rollers but it also serves as a bearing sleeve to support a rolling load. Supported by each bearing sleeve, and in rolling engagement with each of these sleeves, is a journal roller 40, each of which is mounted upon a shaft or journal 41, which shafts are carried by the table rolls 42 at each end thereof. Preferably the journal rollers 40 are of substantially the same diameter as the rolls themselves, and as shown each of these rollers is held firmly upon its accompanying journal shaft by means of a taper fit connection. As is clear from the disclosure of the drawing each of these rollers 40 is supported by two adjacent roller bearings, each roller being in rolling contact with the bearing sleeves of two adjacent bearings. As a result of this construction if any one table roll rotates its accompanying journal roll 40 will tend to rotate the two bearing sleeves by which it is supported, and will thus transmit rotary motion to the two journal rollers 40 positioned on each side of it, and each of these in turn will tend to impart rotary motion to the journal rollers positioned adjacent to it. Consequently so long as any one table roll rotates the remaining rolls which are supported within same housing will also be caused to rotate.

Despite the fact that the table rolls are driven by the forming wire so that end thrust of these rolls would not be expected, nevertheless there is such end thrust, and as a result during operation wear will take place. In order to compensate for any such wear and prevent end play, and to take up end thrust which is especially pronounced, of course, where the table rolls are mounted on a shaking forming section, an adjustable thrust receiving bolt 45 is mounted within the wall of the housing adjacent the end of each journal shaft 41. By proper adjustment each of these bolts may be caused to contact with the end of its cooperating journal shaft so that it will take up all the thrust. A suitable lock nut 46 is provided for holding each of these thrust bolts in ad-

justed position. As shown particularly in Fig. 3 the housing is divided in two horizontal planes to form the upper and lower sections and so the thrust bolts are threaded-
5 ly mounted within one section.

Preferably each bracket 1 is provided with a bolt 48, which is threadedly mounted within a suitable opening 49, tapped in each of the inner-race members 35 associated with 10 the two end bearings. These two bolts 48 thus tend to restrain the housing against movement, and hold it in properly adjusted position.

Each of the inner-race members 30 is 15 provided with a pin 50, which locks each of these inner-race members against rotative movement.

The body portion 10 of the housing is provided with a plurality of upwardly extending partitions 55 which divide this lower portion of the housing into compartments, these partitions serving as baffles to prevent the flow of oil along the housing when it is in inclined position during operation. 20 During operation the table rolls generally have a surface speed of rotation of about a thousand feet per minute and of course the journal rollers 40 have the same speed. At this speed of rotation these rollers will 25 pick up lubricant and carry it on their surfaces, some of the lubricant being carried over to the cooperating bearing sleeve and so on the entire length of the housing, and some of the lubricant being thrown off from 30 the rotating journal rollers. Effective lubrication of each of the roller bearings and of the contacting rolling faces of the journal rollers and the bearing sleeves is thus insured. Positioned within the top section of 35 the housing adjacent the last journal roller is a scraper 56, which cooperates with the surface of the last journal roller and serves to strip the oil from it. This oil runs along the inclined surface of this scraper and collects in the pocket 57. Connected to the 40 bottom of this pocket is a pipe 58, the other end of which opens, as shown at 59, into the bottom portion 10 of the housing. In actual practice it is found that the oil is so scattered, as it is flung off from the rotating journal rollers that uniform distribution of the oil throughout the apparatus with resulting uniform lubrication will be assured, 45 even though the side rail and the housing carried thereby are inclined at a considerable angle. But if the oil should be impelled by the surfaces of the revolving rolls from one end to the other at a rate which would tend to cause an accumulation of the oil at the lower end of this housing the scraper 56 would strip the oil from this last roll and return it through the pipe 58 to the upper end of the housing so that a continuous circulation of oil would thus be secured.

60 During operation, apparatus of this char-

acter is continuously splashed with water and it is therefore desirable that leakage of water into the housing be prevented. It is also desirable that the leakage of oil out of the housing be prevented. In order to 70 accomplish this each journal shaft 41 has a sleeve 60 slidably positioned thereon which sleeve is constrained to rotate with the journal shaft by means of a pin and slot connection 61; which, however, allows free longitudinal sliding of the sleeve. At that end which is adjacent the housing each sleeve is provided with an outstanding flange 62, the 75 face of the sleeve and flange being machined to cooperate with the corresponding machined surface 63 on the housing. The other end of each sleeve is recessed to overlie the hub of the table roll and a spring 64 is positioned within this recessed portion to urge the machined surfaces of the sleeve 80 and housing together. The surface 63 is provided with a circular groove 65, to which is connected a passage 68, which opens into the interior of the housing. As a result of 85 this construction there is a tendency to throw off any water which falls upon the sleeve 60 due to the rotary motion. In addition inward leakage is prevented by the closely fitting surfaces, so that the entrance of water 90 into the housing is prevented. Furthermore leakage of oil out of the housing is also prevented for any oil tending to work between the surface 63 and the contacting surface of the sleeve will be caught by the circular groove 65 and returned to the housing. 95

While the form of apparatus herein described constitutes a preferred embodiment of the invention, it is to be understood that the invention is not limited to this precise form of apparatus, and that changes may 105 be made therein without departing from the scope of the invention which is defined in the appended claims.

What is claimed is:

1. In a paper-making machine, comprising a side rail, and a plurality of table rolls supported thereby; a plurality of bearing members supported by said side rail and positioned to receive the said table rolls in rolling engagement, the construction being such 110 that each bearing member as it rotates tends to cause corresponding rotation of one or more table rolls.

2. In a paper-making machine, comprising a side rail, and a plurality of table rolls; a plurality of bearings supported by said side rail, and rotatable sleeves in said bearings positioned to receive the said table rolls in rolling engagement, the construction being such that each rotatable sleeve is in rolling 115 engagement with two table rolls.

3. In a paper-making machine, and in combination, a side rail, a plurality of roller bearings carried by said side rails, said bearings having rotatable sleeves therein con- 120

structed to receive a revolving load; a plurality of table rolls, journal rollers carried by the said table rolls, each said journal roller being positioned for rolling engagement with two of the said bearing sleeves.

4. In a paper-making machine, and in combination, two spaced side rails, a plurality of spaced bearing members mounted upon each of the said side rails, each side bearing member comprising a rotatable sleeve adapted to receive a revolving load; a plurality of table rolls, a journal roller at each end of each of said rolls, the said bearing members being positioned to receive the said journal rollers in rolling engagement, each journal roller being in rolling engagement with two adjacent bearing sleeves.

5. In a paper-making machine, the combination of a side rail, a roller bearing mounted thereon; a table roll, a supporting journal member therefor, and a roller carried by the said journal member and positioned for rolling engagement with the roller bearing.

6. In a paper-making machine, the combination of a side rail, a roller bearing mounted thereon, a rotatable bearing sleeve in said bearing constructed for receiving a revolving load; a table roll, and a supporting journal member therefor, positioned for rolling engagement with the said bearing sleeve.

7. In a paper-making machine, the combination of a side rail, a roller bearing mounted thereon, a rotatable bearing sleeve therein constructed for receiving a revolving load; a table roll, a supporting journal member therefor, a cylindrical enlargement mounted on said journal member and positioned for rolling engagement with the bearing sleeve.

8. In a paper-making machine, the combination of a side rail, a roller bearing mounted thereon, a rotatable bearing sleeve therein constructed for receiving a revolving load; a table roll, a supporting journal member therefor, a cylindrical enlargement mounted on said journal member and positioned for rolling engagement with said bearing sleeve, said enlargement being of substantially the same diameter as the table roll.

9. In a paper-making machine, of the character described, the combination of a side rail, a plurality of roller bearings each provided with a bearing sleeve constructed for receiving a revolving load; and a table roll supported in rolling engagement by two adjacent bearing sleeves.

10. In a paper-making machine, the combination of a side rail, a plurality of roller bearings mounted thereon, a rotatable bearing sleeve in each of the said bearings constructed for receiving a revolving load; and a plurality of table rolls, there being one

less table roll than there are bearings, each roll being supported by two adjacent bearing sleeves.

11. In a paper-making machine, the combination of a side rail; a closed housing adjustably connected to said side rail, a bearing therein having a rotatable bearing sleeve constructed for receiving a revolving load; and a table roll supported in rolling engagement by said bearing sleeve. 70

12. In a paper-making machine, the combination of a side rail; a housing adjustably connected to said side rail, a plurality of bearings within said housing, each comprising a rotatable bearing sleeve constructed to receive a revolving load; and a plurality of table rolls supported in rolling engagement by said bearing sleeves. 80

13. In a paper-making machine, the combination of a side rail; a housing adjustably connected to said side rail, a plurality of bearings mounted therein, each bearing having a rotatable bearing sleeve constructed to receive a revolving load; a plurality of table rolls, and a supporting journal member carried by each of said rolls and positioned in rolling engagement with two adjacent bearing sleeves. 85 90

14. In a paper-making machine, the combination of a side rail; a housing adjustably connected to said rail, a plurality of spaced bearings therein, each comprising a rotatable bearing sleeve constructed to receive a revolving load; a plurality of table rolls, there being one less table roll than there are bearings, a supporting journal member carried by each table roll, and a cylindrical enlargement mounted on each said supporting journal member and positioned in rolling engagement with two adjacent bearing sleeves; the construction being such that rotating motion imparted to any one table roll will be transmitted through the cylindrical enlargement on the journal member thereof to the two bearing sleeves in rolling engagement with said enlargement, and in turn transmitted by each of those sleeves to the cooperating table rolls. 100 105

15. In a paper-making machine, the combination of a side rail; a housing adjustably connected to said side rail, a plurality of bearings therein constructed for receiving a revolving load; a table roll, a supporting journal member therefor supported in rolling engagement within the housing by the said bearings; and means for adjusting the positioning of said housing to effect proper positioning of the said table roll. 110 115

16. In a paper-making machine, the combination with a side rail, and a plurality of table rolls; of a housing, a plurality of rotatable bearing sleeves therein, a plurality of table roll journal rollers in rolling engagement with said bearing sleeves, said housing being constructed to contain a supply 120 125 130

- of lubricant, the construction being such that during operation the bearing sleeves and the cooperating journal rollers will cause lubricant to travel along the said housing; and a return pipe connecting the opposite ends of the said housing for returning lubricant from one end to the other to permit its recirculation.
17. In a paper-making machine, the combination with a side rail, and a plurality of table rolls; of a housing, a plurality of bearings mounted therein each comprising a rotatable bearing sleeve; a plurality of table roll journal rollers positioned in rolling engagement with the said bearing sleeves, the housing being adapted to contain a supply of lubricant and the construction being such that during operation the said bearing sleeves and journal rollers cause lubricant to travel along the said housing, a scraper associated with one end journal roller, for removing lubricant from the surface thereof, and a pipe for returning the oil thus removed into the housing at the other end thereof.
18. In a paper-making machine, and in combination a side rail, a table roll, a housing carried by the said side rail, a bearing within the said housing, a journal shaft carried by the table roll and supported within the housing by the said bearing, and means for preventing the passage of water into the said housing.
19. In a paper-making machine, the combination of a side rail; a plurality of bearings associated therewith, each bearing comprising a rotatable bearing sleeve constructed to receive a revolving load; a plurality of table rolls, each table roll having a supporting journal member thereon, a cylindrical enlargement mounted on each supporting journal member and positioned in rolling engagement with two adjacent sleeves; the construction being such that each table roll and two cooperating bearing sleeves are caused to rotate together.
20. In a paper-making machine, the combination of a side rail; a housing adjustably connected to said side rail, a plurality of
- bearings within said housing; a table roll, 50 a journal shaft carried by said table roll and positioned in rolling engagement with the said bearings, within the said housing; and means for preventing leakage of oil from said bearing outwardly along the said 55 journal shaft.
21. In a paper-making machine, the combination of a side rail; a housing adjustably connected to said side rail, bearing means within said housing; a table roll, a journal shaft carried by said table roll extending into said housing and supported by said bearing means; a sleeve slidably mounted upon said journal shaft outside the said housing, and keyed to the said shaft to rotate therewith although freely slidable upon said shaft, a machined surface upon the housing end of said sleeve, a cooperating machined surface upon the housing, and means for urging the said sleeve along the 70 journal member to hold the machined surface thereof in contact with the cooperating machined surface of the housing.
22. In a paper-making machine, the combination of a side rail; a housing adjustably 75 connected to said side rail, bearing means within said housing; a table roll, a hub therefor; a journal shaft mounted within said hub, extending into said housing and supported by said bearing means; a sleeve 80 slidably mounted upon said journal shaft outside the said housing, and keyed to the said shaft to rotate therewith although freely slidable upon said shaft, a machined surface upon the housing end of said sleeve, 85 a cooperating machined surface upon the housing, a recess in the opposite end of the said sleeve receiving the journal hub therein, and a spring within said recess bearing against the said journal hub and the sleeve 90 respectively to urge the said sleeve along the shaft to thus hold the cooperating machined surfaces of the sleeve and the housing in contact.

In testimony whereof I hereto affix my 95 signature.

HERMAN L. KUTTER.
